(57) **CLAIM**

(**) Term: **14 Years**

The ornamental design for a side device and bracket for use with an electronic identification device, as shown and described.

(21) Appl. No.: **29/326,099**

DESCRIPTION

(22) Filed: **Oct. 10, 2008**

FIG. 1 is a perspective view of a side device and bracket for use with an electronic identification device showing my new design;

(51) **LOC (9) Cl.** 14-02

FIG. 2 is a top view thereof;

(52) **U.S. Cl.** **D14/383**

FIG. 3 is a bottom view thereof;

(58) **Field of Classification Search** D14/341-346,

FIG. 4 is a left view thereof;

D14/383-387, 432, 399; D18/4.4, 4.6, 6,

FIG. 5 is a right view thereof;

D18/7; 382/115, 116, 119, 124, 126; 356/71;

FIG. 6 is a front view thereof; and

235/382, 382.5, 449, 483; 355/64, 65, 75,

FIG. 7 is a back view thereof.

355/81; 250/566, 569; D8/349, 382

FIG. 8 is a top view of a bracket thereof for coupling the side device and bracket for use with an electronic identification device shown separately for clarity of illustration only;

See application file for complete search history.

FIG. 9 is a bottom view thereof;

UNITED STATES PATENT AND TRADEMARK OFFICE
CERTIFICATE OF CORRECTION

PATENT NO. : Des. 599,348 S
APPLICATION NO. : 29/326099
DATED : September 1, 2009
INVENTOR(S) : Reyes-Zumeta

Page 1 of 1

It is certified that error appears in the above-identified patent and that said Letters Patent is hereby corrected as shown below:

Title Page

Description, FIG. 8, line 2, delete “and bracket for use with an” and insert -- to the --. The description of FIG. 8 will then correctly appear as “FIG. 8 is a top view of a bracket thereof for coupling the side device to the electronic identification device shown separately for clarity of illustration only;”

Signed and Sealed this

Fifteenth Day of December, 2009

David J. Kappos
Director of the United States Patent and Trademark Office
